William S. Gluck

UNITED STATES PATENT OFFICE.

ABRAHAM LEVINE, OF ELIZABETH, NEW JERSEY.

NAME PLATE FOR BRIEF CASES AND SIMILAR ARTICLES.

Application filed May 29, 1924, Serial No. 716,636.

To all whom it may concern:

Be it known that I, ABRAHAM LEVINE, a citizen of the United States, and having a residence at 457 Walnut Street, in the city of Elizabeth, State of New Jersey, have invented certain new and useful Improvements in a Name Plate for Brief Cases and Similar Articles, of which the following is a specification.

10 This invention relates generally to a name plate and more particularly to the association of a name plate with the locking hasp of the brief case in the form of an attachment thereto.

15 While I have illustrated in the drawings and described in the application my invention as associated with a locking hasp of the brief case, it will be understood that this is done merely for purpose of illustration, and that wherever in this application I make reference to a brief case, it will be understood that this term is to be given its broader significance as including bags, such as Boston bags, salesmen's luggage, in connection with which my invention will show with equal effectiveness.

20 It is frequently the practice to place upon a brief case the name of the one to whom the brief case belongs, in a number of ways, as 30 by painting or stenciling the name directly on the body leather of the case or by engraving the name on the metal parts.

25 This manner of associating a name or other indicia with a brief case is open to the objection that any attempt to change the name or indicia is attended with the consequent difficulty of being compelled to erase partly or wholly, indicia already permanently placed thereon and to replace it, 40 which necessarily will tend to mutilate the brief case where the methods generally heretofore practised are employed.

35 One of the objects of my invention is, therefore, the provision of an arrangement whereby I can associate with a brief case an attachment thereto whereby the name of the person or other indicia can be attached thereto or removed therefrom or replaced therein at will without requiring any other act than that of mere physical removal of an element and its replacement.

45 Where I have attempted to make my attachment such that it is associated with the leather portion of the brief case, I have 50 found on the one hand that it is necessary to mutilate the leather so as to permit of

the association therewith of the attachment which necessarily will introduce into the brief case points of weakness, and in addition, due to the readily rendible characteristics of leather, the attachment will not be held in position in that definite relatively rigid manner which I have found desirable. 60

A further object of my invention, therefore, is the provision of an arrangement whereby my name plate attachment can be associated with the brief case in a manner that will give to the name plate that character of support which I find advisable. 65

In addition, while brief cases are primarily utilitarian, it will be understood that it is also the desire of the manufacturer as well as the user that they shall have characteristics of attractiveness as far as such articles can be given such attractiveness, and this is exemplified by the extent to which the corners and the locking hasps and so on are in the form of ornamental highly polished metal constructions, and the further object of my invention therefore is such an 70 association of my name plate attachment with the brief case that it shall not only be positioned on that part of the brief case which is the most attractive, but it in itself 75 shall also add to the attractiveness of the 80 structure as a whole. In this manner, the function of the name plate as such is served most effectively, because it will be the most attractive and attracting portion of the 85 brief case, and therefore will tend to first 90 center attention.

A brief case of the character at present manufactured, used and sold is generally made up of a leather body and metal parts attached thereto and supported therefrom, 95 which metal parts are generally made in the form of metal stampings attached and intended to be attached to the leather parts and are sold to the manufacturer as separate hardware. My invention also includes the provision whereby the attachment already referred to, shall in itself also be in the form of a metal stamping which can be associated with the metal stampings or hardware already used with brief cases and which can be attached thereto in the simplest manner possible and without the need of any special tools. 100

105 My invention further includes a provision generally of a new and improved name plate attachment to the locking portions of a brief case. 110

For attaining these objects and such other objects as may hereinafter appear or be pointed out, I have illustrated one embodiment of my invention in the drawings wherein—

Fig. 1 is a perspective view of a brief case showing my invention positioned on a hasp plate.

Fig. 2 is a section on the line 2—2 of Fig. 1.

Fig. 3 is a perspective view of the card holding means stamped out of sheet material.

Referring to the accompanying drawings, A is a brief case having a locking or closure element 7 formed preferably of metallic sheathing and comprising the lock 8 and hasp 9 as separate elements thereof. Preferably on the outer face of the portion forming the hasp 9 there is mounted a frame or card holding means 10 of a form ornamenteally and pleasingly conforming in contour to the hasp portion.

Described in Fig. 2 is the attachment 10 above mentioned in conjunction with the hasp 9 of the locking member. This is a frame preferably stamped from a single sheet whose cross-section is that of the shape of a letter U. This frame comprises a wall 11 forming one member or leg of the U and an inner wall 13 slightly shorter forming the bead or retaining wall of the frame. The portion 12 comprises the exposed surface and is that part which forms the lower or loop portion of the U. Integral with the outer wall 11 there are at spaced intervals attaching prongs or spurs 14. In this form of frame there is positioned within the wall 11 and against the bead 13, a name plate 22 and if desired a transparent facing material 23 located therein over such name plate. The frame is thereafter attached to the hasp 9 as will be hereinafter described.

For the purposes of having the name card removable, the frame has its outer wall 11 shortened for a portion of its length as at 15 to such extent as to permit the insertion of the card mentioned, when the frame or holding means is in its final position. In such case an easily bendable or flexible retaining tongue is included at the portion of the wall indicated as 15 and forms the part 16, the same being adapted to be moyed in and out of position when removal of the card or name plate is desired.

Referring to Fig. 2, the hasp portion 9 may be made of metal plate bent upon itself longitudinally in the shape of a U and crimped over the edge of the leather or fabric portion of the container forming an outer face 17 upon which the frame 10 above described may be attached. The outer face is provided with holes corresponding in location to that of the fastening elements or prongs 14, above described.

In locating the frame 10 upon the outer face of the hasp, there may be first located within the frame work abutting the bead portion 13 and held within the retaining outer walls 11 in the following order the transparent protective plate 23 and thereafter the name plate or card 22 to be viewed through the frame 10. With these members therein located, the frame is fastened upon the hasp 9 by positioning the fastening elements 14 within the corresponding holes therein provided, forcing the members 14 through the holes until the edge of the wall 11 abut the face 17 of the hasp. The fastening elements are thereafter upset or bent into engaging relation on the back face of member 17.

The above fastening operation may be accomplished upon a hasp provided to the trade as luggage hardware before attachment to the container or brief case and the combination of hasp and attachment will then receive its final positioning by the manufacturer of the leather or like article; or the hasp and card container may be put up separately, in which case the hasp is provided with standard holes to correspond with the fastening elements positioned on the frame work. In such case it is optional with the buyer of the luggage or brief case to have attached thereto the name plate or card holder. In conditions as in the latter case the fastening elements 14 are located within the holes above mentioned and a mere pressing or hammer blow will serve to upset or bend the fastening elements into engaging relation and thereby attach the card holder into position.

It is also contemplated that hasps or metal portions may have holes located in the same to correspond in position to those on the frame or holding attachment and whenever desired may have the name plate or card holder attached thereon in a manner as above noted by pressing and upsetting the spurs or prongs on the opposite side of the metal sheet forming the hasp.

Though I have described by attachment or name plate or card holder as capable of being attached to metal portions, it is contemplated that my frame or container in itself may serve as a removable and attractive name plate holder for removably locating within its walls the card or name plate and this can be accomplished by making the fastening means of comparatively easily penetrating properties so that a name plate may be attached to leather or fabric portions by pressing or pinching the prongs or spurs into the leather or fabric parts of the brief cases, luggage and the like and upsetting the prongs over the same on the reverse side. In such case the name plate holder may also extend as in Fig. 1 and in itself from the hasp member of the locking device.

Although I have described my lock attachment in combination with a brief case, I contemplate as equally included within the scope of the invention and the appended 5 claim that form of container or luggage such as may require locking elements as a Boston bag, salesmen's sample cases, musical instrument cases, trunks, suit cases and the like where it is desirable to locate names or 10 other indications prominently and in an attractive manner.

Having thus described my invention and illustrated its use, what I claim as new and desire to secure by Letters Patent is—

15 In a brief case an attachment therefor adapted to be attached to the hasp thereof comprising a metallic frame of sheet material bent to form the cross-section which is substantially in the shape of the letter U

having unequal legs, the inner shorter leg 20 forming a shoulder or bead portion and the outer leg forming retaining walls and hasp abutting joints and fastening prongs or spurs integral with the outer wall, said outer wall having a cut-out portion for part its 25 length to form a card insert and removing portion, and a flexible tongue portion projecting from the outer edge of the said cut-out portion forming a closure element for said cut-out portion, the whole being adapted 30 for attachment to the brief case by upsetting or bending the prongs or spurs and serving to retain a name plate or card within its enclosing walls.

In witness whereof, I have hereunto signed 35 my name.

ABRAHAM LEVINE.
